UNITED STATES PATENT OFFICE.

HARRY FORD, OF UTOXETER, ENGLAND.

ARTICLE ADAPTED TO BE USED AS LIGHT-REFLECTOR, VASE, OR THE LIKE.

1,313,806.

Specification of Letters Patent. Patented Aug. 19, 1919.

Application filed January 15, 1918. Serial No. 72,251.

To all whom it may concern:

Be it known that I, HARRY FORD, a subject of the King of Great Britain, and a resident of The Hall, Uttoxeter, Staffordshire, 5 England, have invented a new or improved article adapted to be used as light-reflectors, vases, or the like or decorative slabs for partitions, wall or ceiling covering, or the like, of which the following is the specification.

10 This invention relates to a new or improved process and composition for forming or molding articles such as light reflectors or shades, vases or the like, or decorative slabs for partitions, wall or ceiling covering, 15 columns, pilasters, cornices, pedestals or the like.

Broadly, according to this invention pieces of alabaster or gypsum are provided which may be of varying or uniform sizes.

20 To provide a uniform size the pieces may for this purpose be passed through a sieve or the like. The pieces are thoroughly mixed together with a suitable cement or other adhesive to form a composition or mass. Before the composition solidifies, the same may be poured into molds of the required shape, or the composition in the liquid or plastic form may be rolled or pressed into slabs or 25 columns or other desired form.

30 The pieces of alabaster or gypsum may be reduced by breaking or milling or the like into granular form of the desired sizes which may be regulated by screening or the like.

The sizes of the gypsum chips will vary 35 according to the work for which they are to be employed, and may vary from the granular form for smaller work up to the size of a brick for larger work, slabs and the like, and may be irregular, or of regular cubic 40 form.

The gypsum chips may be colored before mixing or be left in natural color.

Any kind of cement may be employed, for example, Keene's, Parian or Martin's, the 45 latter being a composition having gypsum for its basis and consisting of a mixture of acid and alkali with gypsum, the same being made similar to Keene's cement. It is more or less translucent when polished. It is essential that the fragments or pieces of gypsum are thoroughly mixed together with the cement. The cement or adhesive may for further example consist of vulcanite in the plastic form or be of similar composition or 50 an adhesive.

The cement may be for some kinds of

goods semi-transparent if desired, or may be colored according to requirements.

Pressure may in some cases be employed upon the mixture or composition in the 60 molds not only to insure that the mold is completely filled, but to give a greater density in solidifying to the composition.

When the material has hardened in the mold or in the mass it may be turned and 65 polished, or if in slabs for decorative purposes, it is polished in any known manner.

The resulting article or new manufacture has a very pleasing and decorative appearance, and the cost of production is relatively 70 low.

Electric light bowls, shades or reflectors may be produced in any suitable shape and relatively thin, and of a very effective appearance.

Any suitable work of the kind such as is usually executed in marble slabs, pillars or the like can be produced in this composition at a considerably less cost and can be given an equal polish; the effect is novel and highly 80 decorative.

Reference should be made to the accompanying sheet of drawings in which are shown some examples of the manufacture according to this process and composition. 85

Figure 1 is a plan of a rectangular slab of the finished material as made with Keene's cement, and with pieces of gypsum of irregular size, the front surface of the slab is preferably polished in a like manner to that 90 usually employed in polishing alabaster. When such a slab is employed for wall decoration the back surface is left unpolished.

Fig. 2 represents a similar slab made with screened pieces of gypsum, and Keene's or other suitable cement, which pieces may be colored artificially, or naturally colored pieces may be employed, for example, such as are red, pink, and amber. For wall or ceiling covering purposes, this slab will have only 100 one surface polished, but if used as a screen or the like, both surfaces are polished. When employed for indirect lighting also, both surfaces are polished. Panels of this kind polished on both surfaces having a light 105 or lights secreted behind them transmit light in the desired diffused manner, producing a very pleasing and decorative effect.

Fig. 3 represents a cubic mass of the solidified composition, the composition having 110 been poured into a mold of this form. The composition when in the mold and while

setting may be subjected to pressure either by means of a head of water or by a pump.

Fig. 4 represents a pilaster made with this composition. It is preferably molded in three separate parts, the top or cornice portion, the rectangular central portion and the pedestal portion.

Fig. 5 represents a bowl as used for indirect or diffused lighting purposes. The bowl as shown is formed of irregular pieces of gypsum with Keene's cement, as previously described. When set it is removed from the mold and turned up in a lathe and polished in like manner to that employed with alabaster. A brass beading or ring is then secured to the edge of the bowl having three lugs to which to attach the chains as usually employed for bowls used for indirect lighting.

Fig. 6 represents a bell reflector of ordinary or usual shape or form, made of irregular pieces of gypsum according to this invention. By placing the light, electric for example, well within the bell, the reflector serves not only to reflect light directly downwardly but also to transmit diffused light through the semi-transparent walls of the bell.

The letter A represents irregular pieces of alabaster or gypsum on all the figures and B the cement, while A¹ indicates the cubic or more regular pieces of alabaster in Fig. 2. The lines C in Fig. 3 indicate the saw cuts in the cubic mass by which the cube is preferably harder composition as previously described is divided up into slabs or plates which are afterward polished on one face for wall covering purposes.

In Fig. 4, E represents the rectangular central slab of the pilaster and D and F the top and bottom portions thereof respectively.

In Fig. 5, G represents the chains for supporting the bowl used for diffused or indirect lighting, and H, the metallic beading surrounding the lip of the bowl with which are formed the lugs to which the chains are secured.

I am aware that plasters and plastic materials containing alabaster or gypsum burnt or unburnt, together with cement or other materials have been proposed for plastering

walls, molding objects, etc., but in no case was the gypsum or alabaster stated to be granulated or in pieces to provide the artistic effect obtained by this invention.

What I do claim as my invention and desire to secure by Letters Patent is:—

1. As a new article of manufacture, a light diffuser composed of a solidified compound consisting of pieces of solid material, and a binder, the latter being translucent when set.

2. As a new article of manufacture, a light diffuser composed of a solidified compound consisting of irregular pieces of solid material, and a binder, the latter being translucent when set.

3. As a new article of manufacture, a light diffuser composed of a solidified compound consisting of pieces of gypsum, and a binder, the latter being translucent when set.

4. As a new article of manufacture for light diffusing purposes, composed of pieces of solid material thoroughly mixed with a cement and molded into the desired form, the cement being translucent in the resultant set mass.

5. As a new article of manufacture, a light diffuser composed of pieces of translucent material thoroughly mixed with a binder, the latter also being translucent when set.

6. As a new article of manufacture for light diffusing purposes, composed of pieces of colored material thoroughly mixed with a cement and molded into the desired form, the cement being translucent in the resultant set mass.

7. As a new article of manufacture for light diffusing purposes composed of pieces of differently colored material thoroughly mixed with a cement and molded into the desired form, the cement being translucent in the resultant set mass.

8. As a new article of manufacture for light diffusing purposes, composed of pieces of differently colored gypsum thoroughly mixed with a cement and molded into the desired form, the cement being translucent in the resultant set mass.

HARRY FORD.
